UNITED STATES PATENT OFFICE.

WILLIAM J. HULFORD AND THOMAS P. WALSH, OF LAWRENCE, MASS.

LOOM-HARNESS.

SPECIFICATION forming part of Letters Patent No. 323,421, dated August 4, 1885.

Application filed November 24, 1884. (No model.)

To all whom it may concern:

Be it known that we, WILLIAM J. HULFORD and THOMAS P. WALSH, of Lawrence, in the county of Essex, State of Massachusetts, have 5 invented a certain new and useful Improvement in Loom-Harness, of which the following is a description sufficiently full, clear, and exact to enable any person skilled in the art or science to which said invention appertains to 10 make and use the same, reference being had to the accompanying drawings, forming part of this specification, in which—

Figure 1 is a side elevation of our improved loom-harness; Fig. 2, a vertical section of the 15 same; Fig. 3, a top plan view; Fig. 4, a view of one of the links or holders detached; Fig. 5, a perspective view of one of the sliding catches detached; Fig. 6, a like view of one of the hooks, and Fig. 7 a view of one end of one 20 of the rods.

Like letters of reference indicate corresponding parts in the different figures of the drawings.

The nature and operation of the improvement will be readily understood by all conversant with such matters from the following explanation.

In the drawings, A represents the top rail; B, the bottom rail, and C D the end rails, these 30 parts constituting the body or frame of the harness. A mortise, m, is formed in the inner edge of each end rail near the rails A B, and disposed in these mortises there are two flat rods, E, respectively provided on their outer edges near each end with notches x for receiving the pins d, which are inserted transversely in the end pieces, C D. The mortise m in the upper end of the rail D is provided with a slot, i, opening outwardly from its bottom 40 through the edge of said rail, the mortise m in the lower end of said rail being also provided with a corresponding slot, these slots serving to admit the rods E to said mortises, and also to the mortises in the rail C.

The hook H has a flat body, provided with an elongated slot, h, near its center, and is inserted in a vertical slot (not shown) through the center of the rail A, being kept from escaping from the slot in the rail by means of a 45 pin, k, which passes transversely through the rail and through the slot h in the body of the hook, the rail B being provided with a corre-

sponding hook, H, and pin k, arranged in substantially the same manner as those in the rail A. Each of the hooks H is provided near 5 one end with a notch, r, and downwardly-projecting lip l, and fitted to slide on the top of the rail A there is a catch, J, having an outwardly-projecting flange or thumb-piece, f, at one end, and provided with a depression, z, at 6c the other. The body of the catch is also provided with an elongated slot, b, the catch being held in position on the rail by means of screws v, which pass through said slot into the rail.

The holder M is composed of a single piece of elastic wire bent to form the body w, for receiving the rod E, and having the outwardly-turned hooks a a, to which the wire heddles N, having the eyes g, are attached.

In the use of our improvement the upper hook H is dropped to its fullest extent, and the upper rod E partially withdrawn from the frame through the slot i, leading into the upper mortise, m. A suitable number of the 75 holders M are then slipped onto the rod with their hooks a downward, after which it is reinserted in the upper mortises, m. The upper hook H is then drawn up, engaging the rod E and elevating it until the pins d enter its 80 notches x, after which the slide J is moved horizontally on the rail A to draw its end n into the notch r in the hook H, and cause the lip l to fall into the depression z, thereby locking the slide and rod E in position. A series 85 of holders, M, arranged with their hooks a upwardly, are then strung on the lower rod E in substantially the same manner as described for the holders on the upper rod, after which the heddles N are attached to the upper and 90 lower holders and a "strain" applied to all the heddles by forcing the lower rod E down to its fullest extent and securing it by means of the lower hook H and slide J, in a manner which will be readily obvious without a more 95 explicit description.

The holders may be strung on the upper or lower rod E first, as preferred, and twine heddles may be used instead of the wire heddles, if desired. The rods E yield or spring 100 sufficiently to permit the projecting lips l to enter the depressions z, and act to keep them there when once inserted in said depressions. Equivalent means may, however, be employed

to lock the slide J, if desired, as we do not confine ourselves to the special means shown.

It will be obvious that when one of the heddles N breaks or wears out a new one may be readily inserted by lowering the upper or raising the lower rod E, to slacken the wires; also, that when one of the holders M becomes broken or worn out a new one may be readily substituted and without removing the rod E, 10 if desired, as its hooks *a* may be sprung apart sufficiently to permit the rod to enter the body of the holder.

The pins *d* and notches *x* serve to "center" the rods E, and thereby keep them in the same 15 relative position to each other.

The heddles N may be attached to both the upper and lower holders, M if desired, before the holders are strung on the rods E, and said holders may be provided with one hook *a*, instead of two, if preferred.

Having thus explained our invention, what we claim is—

1. The combination of a heddle-frame provided with mortises in its end rails, heddle-rods the ends of which are free in said mortises, said rods being provided with notches near their opposite ends, pins passing through said end rails and engaging said notched heddle-rods, heddles connected to said heddle-rods, and hooks for retaining said heddle-rods in engagement with said pins, substantially as described. 25

2. The combination of the heddle-frame, the rod E, the hook H, having the lip *l*, and a slide, J, provided with depression *z*, substantially as described. 30

3. The combination of the heddle-frame, the rod E, the hook H, and the slide J, for locking said hook, substantially as described. 35

WILLIAM J. HULFORD.
THOMAS P. WALSH.
